(57) **CLAIM**

The ornamental design for a cover lens for an automotive lamp, as shown and described.

DESCRIPTION

FIG. 1 is a perspective view of a cover lens for an automotive lamp showing our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view.

The ornamental design which is claimed is shown in solid lines in the drawings.

The broken lines shown in FIG. 1 depict portions of a cover lens for an automotive lamp in which the design is embodied that form no part of the claimed design.
